UNITED STATES PATENT OFFICE

MICHAEL E. NEENAN, OF NEW YORK, N. Y., ASSIGNOR TO NEENAN ELEVATOR COMPANY, OF BROOKLYN, NEW YORK, A CORPORATION OF NEW YORK.

ROPE ELEVATOR.

1,073,700.

Specification of Letters Patent. Patented Sept. 23, 1913.

Application filed March 28, 1910, Serial No. 551,914. Renewed February 20, 1913. Serial No. 749,727.

To all whom it may concern:

Be it known that I, MICHAEL E. NEENAN, a citizen of the United States, and a resident of the borough of Manhattan, city, county, and State of New York, have invented certain new and useful Improvements in Rope Elevators, of which the following is a specification.

In the rope elevator system now largely in use, the elevator car is suspended from the hoisting ropes which extend from the car up over the suspension sheave, then down and around the motor driven drum, and then up around another suspension sheave to a drum counterweight. A car counterweight of less weight than the car is usually suspended from an independent rope passing over suitable suspension sheaves and attached independently to the elevator car. The support for the car suspension sheave is mounted upon a rigid beam or framework at the top of the elevator shaft. The drum counterweight and the car counterweight are usually arranged to travel in the same vertical guideway, with the car counterweight above the drum counterweight. In this old form of rope elevator construction, many serious accidents have resulted from the breaking of the motor controller and the running away of the motor. If the motor runs away while the car is ascending, the uncontrolled car is carried rapidly to the top of the elevator shaft and forced into engagement with the sheave supporting framework, causing the breaking of the supporting rope, and the sudden release of the car, which falls with only the car counterweight to resist its downward movement. Since the car counterweight is not sufficient to balance the car, its weight, together with the weight of any load that may at the moment be in the car, will cause the car to fall with increasing velocity until it reaches the bottom of the shaft or its movement is arrested by the safety catches usually mounted upon the car. These safety catches have proven unreliable on numerous occasions, and the falling of elevator cars under the circumstances explained, has resulted in many fatalities.

The object of my present invention is to provide simple and effective means for eliminating the possibility of breaking the car supporting ropes in rope elevator systems. In accomplishing this object, I interpose the

car counterweight between the car supporting ropes and the drum hoisting ropes and place a buffer between said counterweight and the hoisting drum. I also provide a yielding support for the car suspension sheave. As a further element of safety, I prefer to arrange the car supporting ropes of greater strength than the drum hoisting ropes, by employing a greater number of car supporting ropes than drum hoisting ropes.

The details of construction in carrying my invention into practice may be variously arranged. The yielding support for the car suspension sheave is preferably made in the form of a beam supported in normal position by heavy compression springs. This beam may be pivotally mounted at one end, with or without supporting springs, and sustained at its other end by said compression springs. The car suspension sheave is journaled in pillow blocks mounted upon said yielding beam or frame. The compression springs are of sufficient strength to normally withstand the weight of the car and load and connected parts so that in the ordinary operation of the improved elevator construction, there will be no appreciable movement of the frame or beam upon which the car suspension sheave is mounted. In an elevator system having this arrangement of car supporting ropes, yielding support for the car suspension sheave, car counterweight, buffer and hoisting ropes, it will be observed that in the event of the motor running away as above set forth, the car counterweight will first be pulled down against the buffer to partially retard the upward movement of the car, and when the buffer stops yielding, will result in breaking the hoisting ropes which connect the car counterweight with the drum. The hoisting ropes will break in this manner before any unusual strain is placed upon the car supporting ropes, which latter will therefore remain intact. When the hoisting ropes are broken, and the car is relieved in this way from the elevating action of the motor driven drum, the momentum of the car will carry it a short distance upward, when it will drop rapidly and apply its whole weight with a sudden blow to the ropes connecting it with the car counterweight. The yielding support for the car suspension sheave will yield under this sudden blow

and relieve the ropes from the shock with the result that the breaking of the ropes between the car and its counterweight will be avoided.

5 My present invention comprises further a rearrangement of the car counterweight and drum counterweight. I propose to still arrange these counterweights to travel in a common vertical guideway, but will place 10 the car counterweight beneath the drum counterweight. By this arrangement I am able to accomplish several important results, particularly when such arrangement is employed in connection with the yielding 15 support for the car suspension sheave. In the first place, it will be observed that with this arrangement, the counterweights will move up and down in their guideway in unison during the normal operation of the 20 mechanism, but that in the event of the breaking of the hoisting ropes between the car counterweight and the hoisting drum while the car is ascending, the moment the weight of the car is thrown upon its counterweight (the shock being absorbed by the 25 yielding support for the car suspension sheave), the car counterweight will tend to move upwardly as the car goes downwardly, but will not be permitted to proceed very 30 far when it will be arrested by striking against the drum counterweight, which latter is descending under the conditions noted, not only because of the breaking of the 35 hoisting ropes while the car was ascending, but also because of the release of the weight of the car from the hoisting ropes. The mere added weight of the drum counterweight to that of the car counterweight is in itself an element of safety, but in addition to this, I prefer to so form the car and 40 drum counterweights that their sudden engagement will wedge or otherwise clamp them between their guide rails, so that the movement of the car will be arrested before 45 it can fall far enough to cause any material damage. Many different forms of devices can be adopted for causing the two counterweights to automatically bind between their 50 guide rails when they are thrown into engagement, such, for instance, as wedge shaped projections upon the adjacent faces of the counterweights, or an arrangement of toggle levers upon one counterweight in position to be operated by the other counterweight.

In order that my invention may be fully understood, I will first describe the same with reference to the accompanying drawings, and afterward point out the novelty 60 more particularly in the annexed claims.

In said drawings, Figure 1 is a diagrammatic side elevation of a positive drive rope and drum elevator mechanism embodying my invention. Fig. 2 is a detail view of 65 one form of cooperating counterweights.

Figs. 3, 4, 5 and 6 are views similar to Fig. 2 showing modified arrangements of counterweights embodying my invention. Fig. 7 is a view similar to Fig. 1 of a friction drive mechanism showing a further modification and illustrating the use of ropes of greater strength for supporting the car than for hoisting the car, and Fig. 8 is a view similar to Fig. 2 showing the modified arrangement of counterweights illustrated in 75 Fig. 7.

A motor driven hoisting drum 1 of usual construction mounted in the usual manner at the bottom of the elevator shaft or adjacent thereto has passing around and fastened to it a hoisting rope 2 and drum counterweight rope 2^b. The rope 2^b passes upwardly from the drum 1 around a suspension sheave 3 mounted at the top of the elevator shaft and to the end of the rope 85 is properly secured the drum counterweight 5 which operates in the guideway formed by the guide rails 6 and 7 at one side of the elevator shaft. The drum counterweight 5 may be of any suitable construction mounted in the usual way, but is preferably arranged as hereinafter described for accomplishing the purposes of my present invention. The drum counterweight 5 acts in the usual manner to equalize the operation 95 of the mechanism. The hoisting rope 2 passes up from the other side of the hoisting drum 1 and is attached to the bottom of the car counterweight 25 which is mounted in guideways formed by the guide rails 6 and 100 7 beneath the drum counterweight 5. The car counterweight 25 may be variously constructed as hereinafter explained.

The car suspension rope or ropes 2^a are secured to the upper end of car counterweight 25 and extended up through a suitable opening formed vertically in the drum counterweight 5 and over a car suspension sheave 10 and downwardly to the elevator car 15 which is attached in the usual manner. The car counterweight 25 is interposed as a connecting link between the hoisting rope 2 and the car supporting rope or ropes 2^a. The car supporting rope or ropes 2^a are preferably of greater strength than the 115 hoisting rope 2 as hereinafter more fully explained.

The car suspension sheave 10 is journaled at 11 upon the pillow blocks 12 mounted upon the supporting beams or framework 13 journaled at one end as indicated at 14 upon a supporting beam 16 and sustained at its opposite end by one or more heavy springs 20 mounted upon a rigid sustaining beam 21. The spring supports 20 for the beam 125 or frame 13 are of sufficient strength to normally sustain the frame or beam 13 (with the weight of the car, its load, and attached parts) in horizontal position.

Adjacent to the bottom of the guideway 130

formed by rails 6 and 7 is a buffer plate or bar 30 sustained by heavy springs 31 mounted upon stationary beams 32, this buffer being for the purpose of absorbing any 5 shock incident to the end of the downward travel of the car counterweight 25 which is coincident to the ending of the upward travel of the car 15 in the elevator shaft. The spring sustained buffer 30 is also of 10 importance in reducing the shock to the car and the car supporting rope in the event of the motor running away and breaking the hoisting rope.

As explained above, my present invention 15 includes the arrangement of the drum counterweight and car counterweight in the same vertical guideway with the former above the latter for the purpose of presenting the drum counterweight in the path of the car 20 counterweight to resist its rapid ascent caused by the falling of the car in the event of the breaking of the hoisting rope. This result can be accomplished with the described rearrangement of the ordinary forms 25 of counterweights for the drum and car, since the mere added weight of the drum counterweight to that of the car counterweight in the case of the supposed accident will afford material resistance to the falling 30 of the car. I have found, however, that more reliable results can be accomplished by a special construction and arrangement of said counterweights such as shown in my drawings and now to be described.

35 In Fig. 2 I have shown an arrangement for applying a gradually increasing braking pressure. The car counterweight 25 connected above with car supporting rope 2^a and below with the hoisting rope 2, is formed with an upwardly presented projection 35 having an inclined cam surface 36. The drum counterweight 5 is cut away on its lower edge as shown at 37 and pivotally mounted upon counterweight 5 at 38 40 45 is a downwardly presented lever 39 formed with a beveled end 39^a;—one or more stout springs 40 being confined between seats formed at 41 upon the inner face of lever 39 and at 42 upon a vertical shoulder of the 50 counterweight 5. A stop pin or lug 43 upon weight 5 engages the lever 39 to retain it in vertical position with its lower beveled end presented just above the cam face 36 of projection 35 of the car counterweight 25. 55 With this construction and arrangement of the counterweights, it will be observed that upon the close approach of the counterweights by reason of the breaking of the hoisting rope, the beveled end 39^a of lever 39 60 will travel upon the cam face 36 of projection 35 and by the compression of spring or springs 40, will apply a strong and gradually increasing braking pressure between the counterweights and the guide rails 6 65 and 7. This increased friction between the

counterweights and their guide rails will gradually retard the falling of the car.

In Fig. 3 the car counterweight 25 is formed with upwardly presented lugs 45 in which are mounted the toggle levers 46 pivotally connected at 47 and carrying at their outwardly presented ends the brake blocks or shoes 48 which slide upon the guide rails 6, 7. These brake blocks or shoes 48 are pivotally connected at 49 with the ends of the toggle levers 46 and said toggle levers preferably have pin and slot connection with their supporting lugs 45. One of the toggle levers 46 is formed with an upwardly presented head 46^a which is presented directly beneath the drum counterweight 5. A spring 50 is confined between the body of car counterweight 25 and a shoulder 46^b formed beneath one of the toggle levers 46 for the purpose of holding the toggle levers 55 raised above the counterweight 25 with the brake blocks or shoes 48 released from the rails 6 and 7. In this form of the mechanism, the drum counterweight 5 may be of the ordinary construction. In the event of the two counterweights being thrown forcibly together in this construction, it will be observed that the engagement of the drum counterweight 5 with the head 46^a of the toggle levers 46 will actuate said toggle levers to force the brake blocks or shoes 48 against the rails 6 and 7 and thereby apply a powerful frictional resistance to the movement of the counterweights to gradually retard and arrest the falling of the car.

100 In Fig. 4 I have shown a further modification of my invention in which the car counterweight 25 is formed with the upwardly presented cam projection 55, and the drum counterweight 5 is cut off at one corner to form an inclined cam face 56 which is adapted to engage the cam projection 55 of the car counterweight when said counterweights are forcibly brought together. The effect of this form of construction is the 105 jamming of the counterweights between their guide rails for accomplishing the explained purpose.

110 In Fig. 5 I have shown a further modification in which the car counterweight 25 is 115 made of two laterally separating sections 25^a and 25^b. Secured to the bottom of the section 25^b is a laterally extending bar portion 60 having sliding connection with the counterweight section 25^a, and the central 120 portions of the counterweight sections 25^a and 25^b are preferably formed with interlocking tongue and groove portions. In the upper edge of the sectional car counterweight 25^a, 25^b is formed a recess 61 having 125 diverging side walls. The drum counterweight 5 in this form is constructed with a central downwardly presented wedge member 62 having diverging side walls. Upon the forcible coming together of the counter- 130

weights 5 and 25^a and 25^b, the wedge projection 62 will enter the recess 61 and force the two sections 25^a and 25^b of the car counterweight apart to exert a powerful braking pressure upon the guide rails 6 and 7, with the same result explained in connection with the other forms of counterweights.

In the modified form of the invention shown in Fig. 6, the car-counterweight 25 is provided with an upwardly presented projection or lug 65 at one side, while the drum counterweight 5 is provided with a downwardly presented projection 66 at the same side, so that when these counterweights are brought together, they will be thrown askew by reason of the engagement of projections 65 and 66 and will bind between the rails 6 and 7 and effectively resist the downward movement of the car.

In Figs. 7 and 8 I have shown a further modification in which the car supporting ropes are of greater strength than the hoisting rope and a different form of combined car and drum counterweights for retarding the descent of the car in case of accident. I have shown the car 15 supported by two ropes 2^a passing over the suspension sheave 10 and connected to the upper end of an open oblong car counterweight 25^d operating between the guide rails 6 and 7. A single hoisting rope 2 extends from the lower end of the counterweight 25^d to the hoisting drum 1 around which it passes and frictionally engages and then up over the counterweight suspension sheave 3 and down to a drum counterweight 5^a which is mounted in and has sliding engagement with the open frame car counterweight 25^d. In connection with this arrangement, I would have it understood that while I have shown two car supporting ropes 2^a and one hoisting rope 2, this arrangement is only illustrative of the principle by which the ropes for supporting the car are made of greater strength than the rope for hoisting. It will be clear that the same result will be accomplished by having a greater number of car supporting ropes such as three, four, five, six or more, and by having a plurality of hoisting ropes arranged as explained, so long as the hoisting ropes are fewer in number, or are of less tensile strength, than the car supporting ropes. In this modified arrangement shown in Figs. 7 and 8, I provide the same spring supported buffer plates 30 beneath the car counterweight 25^d and in a cut-out or slotted portion of the counterweight 25^d I pivotally mount at 76 a brake block 75 to which is pivoted at 77 a dog 78 operating over a series of rack teeth 79 formed in the upper face of the bottom rail of counterweight 25^d. Coöoperating with this brake block 75 of the car counterweight, is a downwardly extending wedge-shaped projection 80 of the drum counterweight 5^a. With this last described

modified construction, it will be observed that in the event of the motor running away by reason of the breaking of the controller, the hoisting rope 2 will break and leave intact the car supporting ropes 2^a which consist of the bottom rail of counterweight 25^d. The strain upon the supporting ropes 2^a is relieved at the breaking of the hoisting rope by the slight retardation of the upward movement of the car when the car counterweight engages the buffer 30. After the slight upward jump due to the momentum of the car at the moment of breaking of the hoisting rope, the car will start to descend and draw upward its counterweight 25^d. At the same time the drum counterweight 5^a is moving downwardly because of the direction of operation of the runaway motor, and these two counterweights, moving in opposite directions, will draw the cam projection 80 into engagement with the brake lever 75 and force the latter into effective frictional engagement with the side rail 6. The combined weights of the two counterweights 5^a and 25^d augmented by the braking action of the bar 75, will gradually slow up and stop the descent of the car, thereby avoiding serious results.

As hereinbefore explained, the importance of my present invention is the added element of safety in the old form of drum and rope elevator mechanisms by a simple and economical arrangement and modification of the parts of said mechanism. By reason of the yielding buffer arranged between the car counterweight and the hoisting drum, and the yielding support for the car suspension sheave, the car suspension ropes are relieved from the shock of both the sudden stopping of the upward movement of the car, and the sudden starting of the downward movement of the car after the breaking of the hoisting rope, so that the danger of breaking the car suspension ropes is eliminated. Greater safety is insured by making the strength of the car supporting ropes greater than that of the hoisting ropes. In some cases this car counterweight would be supported by an independent cable or rope and not interposed as a part of the hoisting rope. Whether or not the same rope is employed as the hoisting rope and as the support for the car counterweight, the yielding support for the car suspension sheave is of great value in relieving said cable or cables from the shock of the sudden downward movement of the car, the yielding support being of sufficient strength to normally withstand any downward yield of the suspension sheave, but sufficiently sensitive to relieve the apparatus from the shock under the conditions described. This yielding support for the car suspension sheave is of importance in the old arrangement of the apparatus, but is of particular value when used in combination with the improved car counterweight.

5 nation with the novel arrangement and construction of counterweights above described, since it affords an additional element of safety to the suspension ropes when the sudden downward movement of the car is arrested by the automatic engagement of the two counterweights operating as described.

What I claim is:

1. In an elevator system, the combination 10 of an elevator car, a suspension sheave therefor, suitable hoisting means, a rope extending from said car over said sheave to said hoisting means, a buffer mounted adjacent to the course of said rope, and means carried by said rope adapted to engage said buffer and limit the movement of the rope toward the hoisting means.

2. In an elevator system, the combination 20 of an elevator car, a suspension sheave therefor, suitable hoisting means, a rope extending from said car over said sheave to said hoisting means, a car counterweight connected with said rope between said car and said hoisting means, and a buffer mounted 25 in the path of said counterweight to limit its downward travel.

3. In an elevator system, the combination 30 of a car suspension sheave, an elevator car, a car supporting rope extending over said sheave to said car, a car counterweight connected with said supporting rope, suitable hoisting means, a hoisting rope extending from said hoisting means and connected with said car counterweight, and a buffer mounted in the path of said counterweight to limit its downward travel.

4. In an elevator system, the combination 40 of hoisting means, a car suspension sheave, an elevator car, a yielding support for said suspension sheave, a supporting rope extending over said sheave to said car, a car counterweight suitably connected with said car, and a buffer in the path of said counterweight for limiting its downward travel.

45 5. In an elevator system, the combination 50 of a car suspension sheave, a yielding support for said suspension sheave, an elevator car, a supporting rope connected with said car and passing over said sheave, a car counterweight connected with said supporting rope, suitable hoisting means, a hoisting rope connecting said car counterweight with said hoisting means, and a buffer mounted in the path of said counterweight to limit its downward travel.

55 6. In an elevator system, the combination 60 of a car suspension sheave, an elevator car, a supporting rope connected with said car and passing over said sheave, a car counterweight connected with said supporting rope, a hoisting drum, a hoisting rope operating upon said drum and connected with said car counterweight, a buffer mounted in the path of said counterweight to limit its downward travel, a drum counterweight arranged

above and in the same pathway as the car counterweight, and a rope connecting said drum counterweight with said drum.

7. In an elevator system, the combination 70 of an elevator car, a car suspension sheave, suitable hoisting means, a rope connecting said car and said hoisting means and extending over said sheave, a counterweight guideway, counterweights connected respectively with said hoisting means and said car, and mounted to travel in said guideway, one above the other, and means operated by relative movement between said counterweights for applying braking pressure between one of said counterweights and said guideway. 80

8. In an elevator system, the combination 85 of an elevator car, a car suspension sheave, suitable hoisting means, a rope connecting said car and said hoisting means and extending over said sheave, a counterweight guideway, counterweights connected respectively with said hoisting means and said car, and mounted to travel in said guideway, one above the other, and means for applying a gradually increasing pressure between one 90 of said counterweights and said guideway.

9. In an elevator system, the combination 95 of an elevator car, a car suspension sheave, suitable hoisting means, a rope connecting said car and said hoisting means and extending over said sheave, a counterweight guideway, counterweights connected respectively with said hoisting means and said car and mounted to travel in said guideway, one above the other, and means for applying 100 braking pressure between said counterweights and their guideway.

10. In an elevator system, the combination 105 of hoisting means, a car suspension sheave, an elevator car, a supporting rope connected with said car and extending over said sheave, counterweights connected respectively with said hoisting means and said car, said counterweights being mounted to travel in the same guideway with the hoist 110 counterweight arranged above the car counterweight, and means upon said counterweights for applying braking pressure between the counterweights and their guideway in the event of said counterweights being thrown together. 115

11. In an elevator system, the combination 120 of a hoisting drum, a car suspension sheave, an elevator car, a counterweight suspension sheave, a counterweight guideway, a drum counterweight operating in said guideway, a hoisting rope extending from one side of the drum over said counterweight suspension sheave and connected with said drum counterweight, a car supporting rope extending from said drum over said car suspension sheave and connected with said car, a car counterweight suitably connected with said car and operating in said guideway beneath said drum counter- 125 130

weight and means carried by said counterweights for applying braking pressure between the counterweights and their guideway in the event of said counterweights being thrown together.

12. In an elevator system, the combination of a hoisting drum, a car suspension sheave, a yielding support for said sheave, an elevator car, a rope extending from said drum over said sheave to said car, a guideway for counterweights, a drum counterweight operating in said guideway, a rope connecting said drum counterweight with said hoisting drum, and a car counterweight 10 operating in said guideway beneath said drum counterweight and suitably connected with said car.

13. In an elevator system, the combination of a hoisting drum, a car suspension sheave, an elevator car, a guideway for counterweights, a car counterweight operating in said guideway, a rope connecting said car and said car counterweight and extending over said car suspension sheave, a rope connecting said car counterweight with said hoisting drum, a drum counterweight operating in said guideway above said car counterweight, a rope connecting said drum counterweight with said hoisting drum, and 20 means upon said counterweights for applying braking pressure between said counterweights and their guideway in the event of said counterweights being thrown together.

14. In an elevator system, the combination of a hoisting drum, a car suspension sheave, a yielding support for said car suspension sheave, an elevator car, a guideway for counterweights, a car counterweight operating in said guideway, a rope connecting 30 said car and said car counterweight, and extending over said car suspension sheave, a rope connecting said car counterweight with

said hoisting drum, a counterweight suspension sheave, a drum counterweight operating in said guideway above said car counterweight, a rope connecting said drum counterweight with said hoisting drum and extending over said counterweight suspension sheave, and means upon said counterweights for applying braking pressure between the counterweights and their guideway in the event of said counterweights being thrown together.

45

15. In an elevator system, the combination of an elevator car, a car suspension sheave, suitable hoisting means, a rope connecting said car and said hoisting means and extending over said sheave, a counterweight guideway, counterweights connected respectively with said hoisting means and said car 50 and mounted to travel in said guideway, one above the other, and a projection on one of said counterweights adapted to engage a part of the other of said counterweights for applying braking pressure between said counterweights and their guideway.

55

16. In an elevator system, the combination of an elevator car, a car suspension sheave, suitable hoisting means, a rope connecting said car and said hoisting means 60 and extending over said sheave, a counterweight guideway, counterweights connected respectively with said hoisting means and said car and mounted to travel in said guideway, one above the other, and a braking device carried by one of said counterweights 70 adapted to be operated by the engagement of the other of said counterweights to apply braking pressure between the brake-carrying counterweight and said guideway.
